UNITED STATES PATENT OFFICE.

HARRY WEARNE, OF RIXHEIM, GERMANY.

DESIGN FOR WALL-PAPER.

SPECIFICATION forming part of Design No. 29,659, dated November 8, 1898.

Application filed October 18, 1898. Serial No. 693,931. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, which represents a plan view of a portion of a strip of wall-paper embodying the features of my design.

The design consists of a fanciful foliate main figure A, and decorated foliate scrolls B at op-

posite sides of the main figure, which scrolls apparently support a decorated panel C, the panels being surmounted by C-scrolls D, between which scrolls foliage E is arranged in fanciful form.

I claim—

The design for wall-paper herein shown and described.

HARRY WEARNE.
